AIR RIFLE

Hugo Schmeisser, Suhl, Thuringen, Germany

Application May 21, 1936, Serial No. 81,098
In Germany May 21, 1935

6 Claims. (Cl. 124—15)

This invention relates to an air rifle which is similar in form and manipulation to a military rifle and is set by means of a lever, and it has for its primary object considerably to increase the force of the rifle, or in other words the force of the compression spring, without at the same time increasing the force necessary for setting the said lever. An additional object of the invention is to simplify the cocking or setting mechanism as regards the number and embodiment of the parts.

According to the invention the compression spring is cocked by the lever in two stages applied first in one direction to one end of the spring and then in the opposite direction to the other end of the spring.

The compression spring may comprise two separate parts whereby the advantage is obtained of setting these parts of the spring one after the other by the backward and forward movement of the lever. In this case the one compression spring, the outer one, is preferably mounted in a compression sleeve and guided over the air plunger shaft, whilst the second compression spring, the inner one, is mounted and guided in a bore in the said shaft.

According to the invention, the inner compression spring, with the aid of an interposed pressure member likewise provided in the plunger shaft, is compressed in direct fashion by the movement of the lever out of its rear into the forward position, whilst the outer compression spring is compressed upon backward movement of the plunger by means of the lever whereby the spring is compressed between the plunger and an abutment provided in a compression sleeve.

An additional feature of the invention resides in the action of the said lever and the effect of the setting or cocking operation on the charging device of the rifle, a rod connected with the lever acting in such fashion on a rotatable ammunition feed plug provided in the barrel of the rifle that upon withdrawal of the lever the plug is opened and upon the forward movement of the lever the plug is closed.

Additional features of the invention relate to several different safety means; thus for example to a means for preventing withdrawal of the lever when the rifle is cocked and to a means for preventing movement of the handle of the lever except when the latter is situated in its front initial or final position.

The invention will be described more fully 55 with reference to the accompanying drawings,

which illustrate two possible forms of embodiment.

Fig. 1 is a vertical section through those parts of the air rifle to which the invention relates, the rifle being shown in the cocked or set position with the position of the setting means after the preliminary setting operation indicated in broken lines.

Fig. 2 shows the means for preventing backward movement of the lever when the rifle has already been cocked or set.

Fig. 3 is a view similar to Fig. 1 of a modified form of embodiment of the invention.

Fig. 4 is an end view of the means shown in Fig. 2.

In the compression sleeve 1, which at the front is attached to the barrel 2, there moves the air plunger 3 with the shaft 4. About this shaft 4 there is located the compression spring 5, which in the relaxed condition is mounted partially, 20 viz., at the end opposite to the air plunger, in a sleeve 6, which in turn is slideable in the compression sleeve 1 this sliding being bounded towards the rear by a pressure sleeve 7 which bears against the end member 8 closing the compression sleeve at the back.

The setting lever 10, which possesses a grip 11, is mounted to rock about a pin 9. This lever is guided in slots 12 and 13 in the compression sleeve 1 and the shaft 4. The lever 10 has a 30 hump or cam 14 on its rear face which upon backward movement of the lever bears against an abutment 15 at the rear end of the slot 13 in the shaft 4.

There is mounted on a pin 16 provided on the 35 lever 10 a thrust finger 17, the front end of which bears continuously against the outer rear face 18 of the sleeve 6 adapted to accommodate the compression spring 5. In order to prevent the finger 17 and the surface 18 from moving 40 out of contact with one another the corresponding contacting portions, as illustrated by way of example, may be curved.

If the lever 10 is pulled back by hand, the same, 45 owing to the fact that its cam 14 bears against the abutment 15 of the shaft 4, also moves back the said shaft and together therewith the plunger 3, resulting in compression of the spring 5 in its sleeve 6, until the face 18 of this sleeve moves against the pressure sleeve 7 (which is furnished with a slot corresponding with the slots 12 and 13), this being equivalent to the shaft 4 reaching its rearmost position. In this position the trigger member 19 engages a collar 20 on the 50 55

shaft 4, so that the latter is secured against movement towards the front.

Upon the subsequent forward movement of the lever, upon which movement, as already stated, the shaft and the plunger remain in the cocked position, the finger 17 presses against the sleeve 6 and accordingly completely compresses the spring 5.

When, therefore, the extreme forward position of the lever 10 has been reached the compression spring 5 has been compressed to full extent. The handle 11 of the lever 10 is now moved over towards the right transversely to the axis of the barrel in similar fashion to the manipulation of a military rifle.

In addition to the finger 17 there is also mounted on the lever 10, preferably also about the pin 16, a rod 21, which is connected with a plug 22 provided in the barrel 2. When the rifle has not been cocked the bore 23 in this plug forms a part of the barrel 2, and in this position a surface 24 closes the passage between the barrel or bore and the loading aperture 25, so that no bullet or other missile is able to enter the barrel.

When the lever 10 is pulled back, compressing the spring 5, the rod 21 rotates the plug 22 by way of the lever 26 until in the extreme position of the lever 10 towards the rear the bore 23 registers with the loading aperture, so that loading may now be performed without, however, the shot or the like immediately being able to reach the barrel 2, which in this position of the plug 22 is blocked by the surface 24. Upon the additional compression of the spring 5, i. e., when the setting lever is again moved towards the front, the rod 21 operates the plug 22 until the bore 23 again comes into line with the barrel 2. At the same time in this position the passage from the loading aperture 25 to the barrel is again closed. The air rifle is accordingly now set and loaded.

In the drawings the rifle is shown to be of the single-loader type. Naturally, however, it may also be constructed as a magazine rifle without necessitating any fundamental variation in the arrangement above described. It is also possible to dispose the plane of movement of the lever 10 in the horizontal instead of the vertical location, which may be found of advantage in certain instances. In this connection it will be desirable so to construct the grip 11 that it rests against the stock, in which manner there is obtained a greater leverage without appreciably impairing the appearance of the rifle.

In order to prevent the setting lever from being moved back when the rifle is cocked or set, i. e., has not been discharged, there is provided a locking pawl 27 pivoted to a small block 28.

This pawl 27 possesses at its front end a laterally disposed ramp surface 30 projecting within the compression sleeve 4 into the path of the setting lever 10. Upon the forward movement of the pawl 27 for complete compression of the spring 5 the setting lever moves against the ramp and accordingly presses the pawl 27 out of the path of lever 10, against the tension of a spring 31 provided in the block 28 which continuously presses the pawl 27 into the path of the setting lever 10, so that the lever 10 is able to move past the ramp 30. Immediately the lever 10 has passed the ramp 30 the latter is again returned into the path of the setting lever under the action of the spring 31. At the same time a nose or projection 32 on the pawl 27 snaps into a groove or recess 33 in the lever 10, the latter thereby being secured against return movement. Upon press-

ing the trigger 19 the shaft 4 springs forward, and at the same time the collar 20 on this shaft presses against a projection 34 provided on the ramp 30 and extending into the path of the shaft 4, causing this pawl 27 to recede against the action of the spring 31, so that the projection 32 again leaves the recess 33 in the setting lever and accordingly releases the setting lever for its withdrawal. A premature engagement of the projection 32 in the recess 33 and accordingly an unintentional locking of the lever 10 in its front position is avoided by the fact that the position of the pawl 27 so that the projection 32 and the recess 33 cannot engage is ensured by the shaft 4, which in this position of the setting lever retains the pawl 27 and does not release the same until the setting lever, upon its withdrawal, has already passed the projection 32. This operation is made possible by the oblique mounting of the parts 27, 28 shown in Fig. 4 due to which downward movement of the pawl 27 withdraws its nose 32 from the notch 33.

Further, in order to prevent the grip 11 on the lever 10 from being rocked transversely to the axis of the barrel except in the forward position of the setting lever there is provided a safety means as follows:

In a boring within the lower portion of the setting lever 10 there is situated a pin 35, which is pressed continuously upwards by means of a spring, whereby its upper end bears against the lower edge of the grip 11, which edge terminates in a straight line, so that upon the rocking movement of the grip 11 the pin 35 is pressed downwards by the projecting corner in opposition to the spring. During the movement of the setting lever towards the rear and again towards the front until shortly behind the extreme front position this pin is firmly supported by a cam 36 on the finger 17, so that the grip 11 cannot be rocked about the hinge connecting it with the lower part of the setting lever. At that moment when the setting lever again assumes its forward position the pin 35 no longer bears against the cam 36 so that upon the rocking movement of the handle 11 it can enter a recess 37 in the finger 17.

In the second form of embodiment as shown in Fig. 3 the feature of distributing the force over the backward and forward movement of the setting lever is shown in its application to a divided spring.

In the compression sleeve 41, which at the front joins with the barrel 42, there moves the air plunger 43 with the shaft 44. About this shaft 44 there is located a compression spring 45, which is mounted between the plunger 43 and a pressure member 46. The latter bears against a pressure sleeve 47, which thrusts at the rear against the end member 48 closing the compression sleeve 41 at the back.

Within the shaft 44, on the side directed towards the plunger 43, there are provided a second compression spring 49 and a pressure member 50.

The setting lever 52, which possesses a grip 53, is mounted to rock about a pin 51. This lever is guided in slots 54, 55 and 56 in the compression sleeve 41, the pressure sleeve 47 and the shaft 44. The setting lever 52 at the point where upon its backward movement it is loaded by the pressure of the compression spring 45 is furnished with a hump or cam 57 which when the lever arrives at its extreme rear position bears against an abutment 58 at the rear end of the slot 56 in the shaft 44. The setting lever 52 has an-

other hump or cam 59 on its front face, which gears against the pressure member 50 within the shaft of the plunger.

If the lever 52 is pulled back by hand, the same, owing to the fact that its cam 57 bears against the abutment 58 of the shaft 44, also moves back the said shaft and together therewith the plunger 43, the outer compression spring 45 thereby being compressed, i. e., cocked, between the plunger 43 and the pressure disk 46. In this way the spring is always compressed and relaxed in the same direction. When the setting lever 52 has reached its rear position shown in the drawings in broken lines, the spring 45 has been fully compressed. In this position the trigger member 60 rests on the collar 61 of the shaft 44, so that the latter and the plunger 43 are secured against movement towards the front.

Upon the subsequent forward movement of the lever 52, upon which movement, as already stated, the shaft 44 and the plunger 43 remain in the cocked position, the cam 59 of the setting lever 52 presses against the pressure member 50, the inner compression spring 49 situated in the shaft 44 thereby being compressed, i. e., set. In this way the spring 49 also is always compressed and relaxed in the same direction.

After the extreme front position of the lever 52 has been reached the grip 53 is also rocked towards the right transversely to the axis of the barrel, for which purpose the lever 52 and the grip 53 are connected by a hinge 62.

In order, in the second form of embodiment, likewise to prevent the grip 53 of the lever 52 from being rocked transversely to the axis of the barrel except in the forward position of the lever the safety means is preferably constructed as follows:

Within a boring in the setting lever 52 there is provided a pin 63 which is pressed continuously upwards under the action of the spring 64, the same bearing against the straight lower face of the grip 53. Below the pin 63 there is provided a bolt 67, which is shiftable in the transverse direction and in the normal position supports the pin 63 by means of an abutment 65. When the setting lever 52 is located in its extreme forward position the bolt 67 bears against a surface 68 on the gun stock and is pressed back in opposition to the spring 66. In this way there is formed a space available for the longitudinal displacement of the pin 63 downwards and into which the pin 63 is able to enter upon the rocking of the grip 53 by reason of the projecting corner 55 at its lower edge.

In every other position of the grip, i. e., upon the backward and forward movement, the pin 63 is supported by the surface 65 again drawn inwards, so that the grip 53 is locked against lateral rocking movement.

What I claim as new and desire to secure by Letters Patent is:

1. In an air rifle, a compression spring adapted to produce the force of discharge, a lever for compressing the said spring in two successive movements towards the rear and towards the front, a handle hinged to said lever capable of turning laterally thereto and means for preventing turning of the said handle on the lever except in the extreme forward position of the lever, the said means comprising a pin adapted to slide within the said lever upon turning of the handle, a cam supporting the said pin, and a recess in the said cam situated below the pin in the extreme forward position of the lever.

2. In an air rifle, a compression spring adapted to produce the force of discharge, a lever for compressing the said spring in two successive movements towards the rear and towards the front, a handle hinged to said lever capable of turning laterally thereto and means for preventing turning of the handle except in the extreme forward position of the lever, the said means comprising a pin adapted to slide within the said lever when the handle is turned, a spring acting on the said pin, and a spring-controlled bolt acting as a support for the said pin.

3. In an air rifle, a compression sleeve, an air plunger in said sleeve, a shaft extending rearwardly of the plunger, compression spring means for operating the plunger in said sleeve, a lever for cocking the spring means said lever being pivotal rearwardly and forwardly about an axis outside said sleeve and guided in slots in the sleeve and shaft, means whereby the spring means is cocked partly by rearward movement and partly by forward movement of said lever, the said two cocking operations being effected upon opposite ends of said spring means, an intermediate hinge in the cocking lever enabling its outermost part forming a handle to be turned with respect to the inner part transversely to the direction of pivoting of the lever, and means for preventing such turning of the handle except when the lever is in forward position.

4. In an air rifle, a compression sleeve, an air plunger in said sleeve, a shaft extending rearwardly of the plunger, compression spring means for operating the plunger, a sleeve slidably in the compression sleeve and fully containing said spring means when cocked and partly containing said spring means when uncocked, a lever for cocking the spring means, said lever being pivotal rearwardly and forwardly about an axis outside said sleeve and guided in slots in the sleeve and shaft, an abutment on the plunger shaft whereby the spring means is cocked partly by rearward movement of the lever, a thrust finger carried by the cocking lever and bearing against the spring means containing sleeve in the forward movement of the cocking lever to complete the cocking of said spring means, the said two cocking operations being effected upon opposite ends of said spring means, an intermediate hinge in the cocking lever enabling its outermost part forming a handle to be turned with respect to the inner part transversely to the direction of pivoting of the lever, and means for preventing such turning of the handle except when the lever is in forward position, said preventing means including a spring operated sliding member in the cocking lever cooperating with a cam surface on the thrust finger.

5. In an air rifle, an air plunger and shaft, spring means operating on said plunger to produce the force of discharge, a lever for compressing the said spring means in two successive movements towards the rear and towards the front, and means for preventing rearward movement of said lever when the spring means is compressed, said means including a spring pressed pawl extending obliquely into the path of the lever and arranged to yield to allow the lever to pass the pawl in its forward movement but then to engage and hold the lever in its forward position, said pawl having a ramp surface cooperating with the plunger shaft when the rifle is fired to disengage the pawl from the lever.

6. In an air rifle, a compression sleeve, an air plunger in said sleeve, a shaft extending rear-

wardly of the plunger, compression spring means for operating the plunger in said sleeve, a lever for cocking the spring means said lever being pivotable rearwardly and forwardly about an axis below said sleeve and extending upwardly through and guided in slots in the sleeve and shaft, means whereby the spring means is cocked in two substantial stages by successive rearward and forward movements of said lever, the said two cocking operations being applied first to one end only and then to the other end only of said spring means, means automatically put out of action on firing the rifle for preventing rearward movement

of the cocking lever when the second cocking operation is completed, said preventing means including a pawl mounted out of the path of travel of the cocking lever but with its nose movable into and out of said path, the lever having a notch engaging said nose to lock the lever in forward position when the spring means is cocked, and the pawl having a ramp surface cooperating with a projection on the plunger shaft to disengage the nose from the notch at the end of the forward movement of the shaft when the rifle is fired. 5

HUGO SCHMEISSER.
